UNITED STATES PATENT OFFICE.

EDWARD A. JOHNSTON, OF STERLING, ILLINOIS.

SELF-BINDER FOR HARVESTERS.

No. 801,988.

Specification of Letters Patent.

Patented Oct. 17, 1905.

Application filed March 13, 1905. Serial No. 249,798.

To all whom it may concern:

Be it known that I, EDWARD A. JOHNSTON, a citizen of the United States, residing at Sterling, Whiteside county, State of Illinois, have 5 invented certain new and useful Improvements in Self-Binders for Harvesters; and I do hereby declare the following to be a full, clear, and exact description of the invention, such as will enable others skilled in the art to which 10 it appertains to make and use the same.

The invention relates to self-binders for grain-harvesters and the like, and relates more especially to the means for throwing the binding devices into and out of action at the beginning 15 and completion, respectively, of the operation of binding the bundles. It is essential to the efficient working of these machines that the binding devices should start easily and promptly on the accumulation of sufficient 20 grain to exert the predetermined amount of pressure on the trip-hook, and it is equally necessary that these devices should be thrown out of operation without the rebound which the shocks and jars that are incidental to the 25 intermittent operation are liable to cause.

With these ends in view the invention consists in a novel construction and manner of operating the trip-stop, so that at the proper time it is thrown out of the way of the roller 30 on the crank of the trip-shaft to permit the trip-hook to fall out of the way of the bundle and allow the latter to be discharged, also so that the trip-stop will be returned to position promptly on the descent of the needle and in 35 so doing will assist the restoration of the trip-hook into operative position and aid in throwing the binder home and will also form a back-stop to counteract the rebound.

The invention is illustrated in the accompanying drawings, where—

Figure 1 is a plan view of a binder attachment with my invention applied. Fig. 2 is an end view of the same looking from the front of the machine. Fig. 3 is an end view looking 45 from the rear side of the machine, the knotter-shaft and mechanism being omitted and part of the frame-casting being shown in dotted lines. Fig. 4 is a detail view showing in section in full lines the trip-stop and its carrier, 50 the trip-dog being shown in dotted lines; and Fig. 5 is a cross-section of the part shown in Fig. 2 on the line 5 5 looking upward in the direction of the arrows.

Referring to the views, *a*, wherever occurring, indicates parts of the binder-frame casting, which is or may be of any preferred con-

struction. Power to drive the binder is taken from the packer-shaft *b*, which is driven in the usual way by a chain belt *b'* and has a bevel-pinion *c* on its forward end. The pinion 60 *c* meshes with a gear *d* on the lower end of a shaft (not shown) that is journaled in the vertical part of the binder-frame casting and carries a beveled pinion *e* at its upper end. This pinion meshes with a bevel-gear *f*, which is 65 loosely mounted on the knotter-operating shaft *g*, that is journaled in the overhanging part of the frame-casting *a*, so that the gear *f* is constantly driven from the packer-shaft.

The needle *i* is mounted, as usual, on the 70 shaft *h*, that is oscillated from an intermittently-rotated cam-disk *l*, fast on the knotter-operating shaft close alongside the gear *f*, the needle-shaft being connected to this cam-disk by the usual pitman *j* and crank-arm *k*, 75 so that the needle-shaft and knotter-operating shaft are actuated concurrently, the former being given an oscillation to cause the needle to apply the band around the bundle and the other being given a single revolution to cause 80 the knotter mechanism to tie the knot.

It being understood that the gear *f* is constantly driven, the cam-disk *l*, which is the immediate driver for all the binding devices except the packers, is clutched to the gear by 85 the pressure of the grain against the trip-hook *p*. This hook is mounted, as usual, on an arm *q*, projecting from the trip-shaft *r*, and is raised nearly to its operative position by a heel projection *s* from the needle-hub in the 90 ordinary manner. At its forward end the trip-shaft has a crank *t*, carrying a roller which releases a spring-actuated trip-dog 95 when the trip-shaft is rocked and allows the dog to clutch the cam-disk *l* to the gear *f* in a manner well understood in this class of machines. In the present invention this trip-dog, which is denoted by *m*, is pivotally connected at its upper end to a plate-like projection *n*, fast on the outer side of the cam-disk *l*, 100 so that the arm lies flatwise against the side of the disk, as best shown in Figs. 1 and 2. The disk has a peripheral flange on the side next to the gear *f*, and this gear has an annular flange *f'*, which fits within the flange 105 of the cam-disk and has notches or recesses *p'* around its inner periphery. The trip-dog *m* has a projection *m'* extending into the space inclosed by flange *f'* of the gear *f* and carries a roller *o*, which is normally thrown outward by a spring *w*, so as to engage one of the recesses *p'*, and thereby lock the disk and 110

gear together. At its lower end the trip-dog has a lateral projection x , which is in the path of a similar projection u' on a trip-stop u , so that when the dog strikes the stop the spring 5 w is compressed and the roller o is thrown out of the recess p' , thereby disconnecting the cam-disk l from the gear f and stopping the disk, while the wheel continues its rotation.

The trip-stop u has at its lower end a foot 10 u^2 , against which the roller on the crank t of the trip-shaft bears when the cam-disk l is disengaged from the gear f and the binder is out of action. The trip-stop is mounted to slide in a rocking carrier-arm a' , that is pivoted at a^2 to the frame-casting just under the cam-disk l . At its upper end it has the projection u' already referred to, and at its lower end it has an inclined toe u^3 , which is best shown in Fig. 4 and will be referred to later 15 on. The foot u^2 of the trip-stop has a rod b'' secured to it, which extends upwardly and parallel with the body portion of the stop and passes loosely at its upper end through a perforated lug c' on the oscillating carrier-arm 20 a' . A short sleeve d' is loose on the upper end of this rod, and between this sleeve and a collar e' at the lower end of the rod a coiled spring encircles the rod. Outside of this 25 spring another spring h' is coiled, and this spring reacts between the collar e' at the lower end of the rod and the projection c' on the carrier a' at the upper end of the rod. The outer spring holds the trip-stop normally downward, so that its foot u^2 rests against 30 the roller on the crank t of the trip-stop shaft and so that the projection u' at its upper end lies normally in the path of the projection x on the lower end of the trip-dog. This outer spring constitutes the trip-spring proper and 35 has the proper tension to hold the trip-hook p against whatever pressure the binder has been set to start at. The inner spring is not normally under tension and is only intended to come into operation when a bundle of 40 usual size gets into the binder and an increased amount of movement of the trip-stop is necessary to relieve the pressure on the trip-hook and its shaft. At this time the flange on the lower end of the sleeve d' strikes 45 the lug c' and the inner spring begins to act, so that during any further movement of the stop both springs act as compression-springs.

The trip-stop carrier a' is made into the 50 form of a bell-crank lever, as shown in Figs. 3 and 4. It is held normally in position with its foot over the roller e^3 of the trip-shaft arm t by a spring e^2 , secured at its upper end to a lug l' on the binder-casting and preferably 55 bowed, as shown in the drawings, so as to operate against the lower arm a^4 of the trip-shaft carrier.

After the binder has been tripped into action, as already described, and the bundle has 60 been bound the foot of the trip-stop must get

out of the way of the roller e^3 in order to permit the trip-hook to fall and release the bundle. This is effected by a cam-rim b^4 , that is formed on the disk l . This disk rotates in the direction of the arrow, Fig. 3, and just 65 after the knot has been tied it strikes a roller c^4 on the upper arm of the trip-stop carrier and swings the carrier from the position shown in full lines in Fig. 3 to that shown in dotted lines, thereby releasing the roller e^3 70 and permitting the trip-hook to fall beneath the deck, as shown in dotted lines.

After the bundle has been discharged it is necessary that the trip-hook should be brought up promptly into position to receive the next 75 bundle. This is effected, as already described, by the projection s from the needle. After the needle is down it is necessary that the arm q , which carries the trip-hook, should be raised slightly from the projection s on the 80 heel of the needle, so as to allow the hook p to have sufficient movement to trip the binder. This is effected by the spring e^2 throwing the lower arm of the trip-stop carrier forcibly 85 outward, so that its inclined toe u^3 strikes the 90 roller on the arm t of the trip-shaft, forcing it down into the position shown in full lines in all the figures.

As shown in Fig. 3, the rim b^4 extends only about half-way around the cam-disk l , and its 95 rear end is inclined outwardly, as shown at t^5 . The disk reaches the position shown in this figure immediately after the bundle has been discharged, and, as will be seen from the drawings, the roller c^4 is then free to leave 100 the cam under the tension of the spring e^2 , which presses the lower arm of the trip-stop carrier outward. This forces the roller c^4 to ride upon the inclined tail t^5 of the rim b^4 and not only helps to throw the binder home, but 105 in case the cam should tend to rebound prevents any movement of the disk in the reverse direction to that of the arrow in the figure.

As before stated, the trip-dog is pivotally connected to the cam-disk l and lies flatwise 110 against its outer side. It is held normally in position to lock the cam-disk to the gear f' by the spring w , and the dog necessarily has considerable play. For this reason I provide a lug t^6 on the disk l just behind the dog, so 115 that when the lower end of the dog strikes the trip-stop and its roller o is disengaged from the notches of the gear f the lug will immediately engage the rear edge of the dog, the play between the parts will be taken up, 120 and a rigid connection will be established between the dog and the disk, thus forming a substantial stop to receive the blow caused by the dog striking the trip-stop.

The arrangement and operation of the several parts being as thus described, it will be noted that the construction of the binder is light and strong and that the manner of mounting the trip-hook in an oscillating carrier and swinging it as and by the means de- 125 130

scribed insures in the first place that there shall be no impediment to the free and easy discharge of the bound bundle and in the next place that provision is made for promptly and easily restoring the parts into position ready for another bundle without liability of the shocks and jars causing the binder to rebound.

Except as hereinafter claimed there is no particular novelty in the construction or arrangement of any of the parts of the binder; but I do not intend to be limited to the particular construction or arrangement of the oscillating trip-stop carrier or any of the other parts forming features of the present invention.

Having thus described the invention, what I claim, and desire to secure by Letters Patent, is—

20 1. A self-binder, having in combination a pivoted vertically-swinging trip-stop, a trip-hook, a trip-hook shaft, a crank on the trip-hook shaft under the foot of the stop, and a cam on the knotter-operating shaft for swinging the stop out of the way of the crank to permit the hook to fall.

25 2. A self-binder having in combination a vertically-swinging trip-stop, a trip-hook, a trip-hook shaft having a crank, means for swinging the stop out of the way of the crank so that the said hook may fall, and means for forcing said stop against said crank prior to the completion of its return movement, said stop being adapted to force said crank out of 35 its path and thereby throw the crank and its connected hook into position.

30 3. A self-binder, having in combination a pivoted vertically-swinging trip-stop, a trip-hook, a trip-hook shaft having a crank, means for swinging the stop with its foot over the crank to restore the trip-hook to position, and a cam on the knotter-operating shaft coöperating with the stop to prevent rebound of the 35 binder.

40 4. A self-binder, having in combination a pivoted vertically-swinging trip-stop, a trip-hook, a trip-hook shaft having a crank, a cam on the knotter-operating shaft for swinging the stop out of the way of the crank to per-

mit the hook to fall, a spring for returning 50 the stop with its foot over the crank to restore the trip-hook to position, the stop-swinging cam on the knotter-operating shaft having a deflection at its rear end to coöperate with the stop and prevent the rebound of the 55 binder.

5. In a self-binder, the combination of the trip-hook shaft, the trip-hook, a crank on the shaft, and a trip-dog, the trip-stop comprising a pair of springs, only one of which is 60 under tension in the tripping movement of the stop, and the other of which is put under tension by any further movement of the stop.

6. The combination to form a trip-stop for self-binders, of a carrier, a trip-stop sliding 65 therein and having a foot, a rod connected to the foot and sliding through a lug on the carrier, a sleeve loose on the upper end of the rod, a spring not under tension located between the sleeve and a collar on the rod, and 70 a spring under tension between the rod and the lug on the carrier.

7. The combination to form a trip-stop for self-binders, of a trip-stop, an oscillating carrier therefor, consisting of a two-armed pivoted lever in bearings in one arm of which the stop slides, a rod connected to the foot of the stop and sliding through a lug on the arm of the carrier, a sleeve loose on the upper end 75 of the rod, a spring not under tension located between the sleeve and a collar on the lower end of the rod, and a spring under tension between the rod and the lug on the arm of the carrier.

8. In a self-binder, the combination of the 80 knotter-operating shaft, a continuously-operating gear thereon, a disk fast on the shaft, a trip-dog pivotally connected to the disk and acting to lock the disk and cam together, a stop for tripping the dog, and a lug on the 85 disk behind the dog against which the dog strikes when it is tripped.

In testimony whereof I affix my signature in presence of two witnesses.

EDWARD A. JOHNSTON.
